Primary Examiner—Kay H. Chin*Attorney, Agent, or Firm*—Schwegman, Lundberg & Woessner[57] **CLAIM**

The ornamental design for a child carrier attachable to a shopping or luggage cart, as shown and described.

DESCRIPTION

FIG. 1 is a front perspective view of a child carrier attachment to a shopping or luggage cart showing my new design, the broken lines are for illustrative purposes only and form no part of the claimed design;

FIG. 2 is a top plan view of thereof;

FIG. 3 is a front elevational view thereof;

FIG. 4 is a side elevational view thereof, the opposite side view being identical;

FIG. 5 is a rear elevational view thereof;

FIG. 6 is a bottom plan view thereof;

FIG. 7 is a front perspective view of a second embodiment of the child carrier attachment to a shopping or luggage cart;

FIG. 8 is a top plan view of FIG. 7;

FIG. 9 is a front elevational view of FIG. 7;

FIG. 10 is a side elevational view of FIG. 7, the opposite side view being identical;

FIG. 11 is a rear elevational view of FIG. 7;

FIG. 12 is a bottom plan view of FIG. 7; and,

FIG. 13 is a front perspective view of FIG. 1 with the luggage cart in phantom.
